UNITED STATES PATENT OFFICE

91,996

DESIGN FOR A CARD FOR A CHEMISTRY CARD GAME

Dennis A. Forbes, Nashville, Tenn.

Application May 12, 1933, Serial No. 48,091

Term of patent 7 years

To all whom it may concern:

Be it known that I, DENNIS A. FORBES, a citizen of the United States, residing at Nashville, in the county of Davidson and State of Tennessee, have invented a new, original, and ornamental Design for a Card for a Chemistry Card Game, reference being had to the accompanying drawing, forming a part thereof.

Figure 1 is a front elevation of the card, showing my new design.

Figure 2 is a rear elevation thereof.

I claim:

The ornamental design for a card for a chemistry card game as shown.

DENNIS A. FORBES.
